(57) **CLAIM**

I claim the ornamental design for a chimney protector, as shown and described.

DESCRIPTION

FIG. 1 is a perspective view of my design;

FIG. 2 is a back elevational view of my design;

FIG. 3 is a front elevational view of my design;

FIG. 4 is a top view of my design;

FIG. 5 is a bottom view of my design; and,

FIG. 6 is a side view of my design, the opposite side view being a mirror image thereof.

The features shown in broken lines, if any, are shown for illustrative purpose only and form no part of the claimed design.

1 Claim, 2 Drawing Sheets

FIG. 4

FIG. 5

FIG. 6
